(57) CLAIM

The ornamental design for a folding knife with replaceable blade, as shown and described.

DESCRIPTION

FIG. 1 is a perspective view of a folding knife with replaceable blade, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-sectional view of the folding knife with replaceable blade of FIG. 2; and,

FIG. 10 is an enlarged view of portion 10 shown in FIG. 2. The broken lines in the drawings depict portions of the folding knife with replaceable blade that form no part of the claimed design.
